DESIGN FOR AN END FRAME FOR CAR-SEATS.

No. 38,687.

Specification for Design.

Patented July 16, 1907.

Application filed May 1, 1906. Serial No. 314,721. Term of patent 7 years.

To all whom it may concern:

Be it known that I, EDWARD G. BUDD, a citizen of the United States, residing at Philadelphia, in the county of Philadelphia and State of Pennsylvania, have invented a new, original, and ornamental Design for End Frames for Car-Seats, of which the following is a specification, reference being had to the accompanying drawings, forming part hereof.

In the drawings, Figures 1 and 2 are views

in elevation of an end-frame for car-seats embodying my new design, one view being taken at right angles to the other.

I claim:

The ornamental design for an end-frame for car-seats as shown.

EDWARD G. BUDD.
